[57] CLAIM

The ornamental design for a cart, as shown and described.

DESCRIPTION

FIG. 1 is a top and front perspective view of a cart showing my new design;

FIG. 2 is a top plan view thereof;

FIG. 3 is a side elevational view thereof, the opposite side view being a mirror image of that shown;

FIG. 4 is a bottom plan view thereof;

FIG. 5 is a front elevational view thereof; and

FIG. 6 is a rear elevational view thereof.
